UNITED STATES PATENT OFFICE.

ERNEST E. SUTHERLAND, OF MANSFIELD, OHIO, ASSIGNOR TO WESTINGHOUSE ELECTRIC & MANUFACTURING COMPANY, A CORPORATION OF PENNSYLVANIA.

ELECTRIC HEATING UNIT.

Application filed January 25, 1924. Serial No. 688,380.

To all whom it may concern:

Be it known that I, ERNEST E. SUTHERLAND, a citizen of the United States, and a resident of Mansfield, in the county of Rich-
5 land and State of Ohio, have invented a new and useful Improvement in Electric Heating Units, of which the following is a specification.

My invention relates to electric heating 10 devices and particularly to electric heating units.

The object of my invention is to provide a relatively simple, compact and light-weight open electric heating unit.

15 In practicing my invention, I provide an upper and a lower skeleton frame of cast metal and a plurality of bars, of refractory electric-insulating material, located therebetween and having interfitting tongue and groove portions respectively. A plurality of resistor members extend through openings in the bars and are each symmetrically distributed over the unit.

In the single sheet of drawings,
25 Figure 1 is a top plan view with portions cut away and a portion shown in section, of a heating unit embodying my invention.

Fig. 2 is a view in end elevation thereof, Fig. 3 is a view, in vertical section there-
30 through, taken on the line III—III of Fig. 1,

Fig. 4 is a view, in front elevation, of a refractory bar constituting a part of the heating unit,

Fig. 5 is a view, in end elevation, of the 35 refractory bar illustrated in Fig. 4, and Fig. 6 is a fragmentary view, in longitudinal section, taken on the line VI—VI of Fig. 4, of the refractory bar.

A heating unit 11 comprises a lower skele-
40 ton frame 12 and an upper complementary skeleton frame 13, each of cast metal, preferably of cast iron. Both frames comprise a relatively narrow peripheral portion 14, and a plurality of laterally extending rib members 15 and 16, respectively. In addition, the bottom frame comprises a plurality of feet 17 located at the corners of the substantially rectangular peripheral portion 14.

50 A plurality of handles 18 are cast integral with the bottom portion 12 and a terminal-supporting and cover member 19 is

also cast integral with the bottom frame, at substantially the middle portion of the side opposite to that at which the handle 55 members 18 are located.

The rib members 15 and 16 in the respective frames, are spaced apart a suitable distance and are provided on the inner surfaces thereof with integral, longitudinally- 60 extending tongue portions 21 and 22, respectively.

Elongated and relatively narrow refractory members 23, of a suitable refractory electric-insulating material are located be- 65 tween the co-operating upper and lower rib members 15 and 16.

The top and bottom surface of the mem-
bers 23 are provided with grooves 24 and
25, within which the respective tongue por- 70
tions 21 and 22 may fit in order to hold the
refractory resistor-supporting member 23
in its proper operative position between the
upper rib member 15 and the lower rib
member 16, which are located in oppositely 75
spaced relation relatively to each other, sub-
stantially as illustrated in Fig. 3 of the
drawings.

Each of the refractory bars 23 is pro-
vided with a plurality of symmetrically 80
spaced openings 26 extending laterally
therethrough and is further provided with
a plurality of longitudinally-extending
grooves 27 in one surface thereof for a pur-
pose to be hereinafter set forth. One of the 85
grooves 27 co-operating with two of the lat-
erally extending openings 26, is more partic-
ularly illustrated in Fig. 6 of the draw-
ing.

A pair of resistor members 28 and 29, 90
each comprising a helically wound resistor
wire of a suitable material, such as ni-
chrome, extend through the respective open-
ings 26 in the spaced bars 23, and also ex-
tend therebetween. Each resistor member 95
extends through the openings 26 and be-
tween the bars 23, in such manner that both
resistor members are distributed substan-
tially uniformly over the surface area of
the heating unit. Three terminal pins 31, 100
32 and 33 are insulatedly mounted in the
member 19 and have the respective ends of
the resistor members 28 and 29 electrically
connected thereto, in such manner that the

two resistor members may be energized in series-circuit relation to each other, one resistor alone, or both in parallel circuit relation relatively to each other, whereby a selective control of the temperature obtained by the use of the heating element is effected. As is shown more particularly in Fig. 1 of the drawing, at each end thereof, one of the helically wound resistor members over 10 laps, in a sense, the other resistor member and as is illustrated in that figure, the resistor member 29 extends through two adjacent openings 26 and the connecting groove 27 therebetween, while the other resistor member 28 extends through openings 28 located adjacent to and on the outside of those openings 26 through which the resistor member 29 extends. By reason of the fact that the walls of the outer openings 26 extend the full thickness of the member 23, the resistor member 28 will lie in a position outside of and spaced from the resistor member 29, and this position will be maintained even though the two resistors are operated at a relatively high temperature 20 and may sag slightly.

Means for holding the two skeleton frames 12 and 13 in their proper operative and superposed positions on each side of the respective members 23 may comprise a plurality of machine screws 34, one of each of which is located at the corner of the skeleton frames. Each of the machine screws 34 is provided with a co-operating nut 35 and a washer 36 of the usual construction.

The device embodying my invention provides a relatively open heating unit in which the major portion of the resistor member is uncovered and heat may be transmitted by 40 radiation only, and it further provides a relatively small amount of supporting material necessary to be heated by the resistor member whereby its initial speed or rate of heating up is greatly increased.

The device embodying my invention further provides a relatively light-weight heating unit comprising a plurality of heating elements, each of which are substantially symmetrically or uniformly distributed over 50 the surface area of the heating unit.

Various modifications and changes may be made without departing from the spirit and scope of the invention, and I desire therefore that only such limitations shall be 55 imposed thereon as are set forth in the appended claims.

I claim as my invention:

1. A light weight electric heating unit comprising substantially coextensive upper and lower skeleton frames, a plurality of spaced and parallel-extending bars, of refractory electric-insulating material, located 60 between said frames, each having a plurality of openings extending laterally there-through, and a resistor member extending

through the openings in said bars and distributed substantially uniformly over the surface area of the heating unit.

2. A light weight electric heating unit comprising substantially coextensive upper 70 and lower skeleton frames, a plurality of spaced and parallel-extending bars, of refractory electric-insulating material, located between said frames, each having a plurality of openings extending laterally there-through and interfitting therewith, means for clamping said frames together, and a resistor member extending through the openings in said bars and distributed substantially uniformly over the surface area of the 80 heating unit.

3. A light weight electric heating unit comprising substantially coextensive upper and lower skeleton frames, a plurality of spaced and parallel-extending bars, of refractory electric-insulating material, located between said frames, each having a plurality of openings extending laterally there-through, said frames and bars having interfitting tongue and groove portions, means 90 for securing said frames against said bars, and a resistor member extending through the openings in said bars and distributed substantially uniformly over the surface area 95 of the heating unit.

4. A light weight electric heating unit comprising substantially coextensive upper and lower skeleton frames, a plurality of spaced and parallel-extending bars, of refractory electric-insulating material, located 100 between said frames, each having a plurality of openings extending laterally there-through, said frames and bars having interfitting tongue and groove portions, means for securing said frames against said bars, a resistor member extending through the openings in said bars and distributed substantially uniformly over the surface area of the heating unit, and terminal members 105 for said resistor insulatedly mounted on one 110 of said frames.

5. In an electric heating unit, in combination, a lower skeleton frame, of metal, comprising a peripheral portion, of substantially rectangular contour, and a plurality of spaced and parallel-extending integral ribs, an upper clamping frame substantially complementary to said lower frame, a plurality of bars, of refractory electric-insulating material each having a plurality of spaced openings extending laterally there-through, said bars having grooved surfaces interfitting with tongue portions on said ribs, means for clamping said upper and lower frames against said refractory bars, and a plurality of resistor members extending through the openings in said bars and each distributed substantially uniformly 120 and symmetrically over the surface area of 125 said heating unit.

6. In an electric heating unit, in combination, a lower skeleton frame, of metal, comprising a peripheral portion, of substantially rectangular contour, and a plurality of spaced and parallel-extending integral ribs, an upper clamping frame substantially complementary to said lower frame, a plurality of bars, of refractory electric-insulating material each having a plurality of spaced openings extending laterally therethrough, said bars having grooved surfaces interfitting with tongue portions on said ribs, means for clamping said upper and lower frames against said refractory bars, a plurality of resistor members extending through the openings in said bars and each distributed substantially uniformly and symmetrically over the surface area of said heat-
- ing unit, and a plurality of terminal members insulatedly mounted on said lower frame. 20
7. An electric heating unit comprising substantially coextensive upper and lower skeleton frames, a plurality of spaced bars, a refractory electric-insulating material located between said frames, each having a plurality of openings extending laterally therethrough, and a resistor member extending through the openings in said bars and distributed over the surface area of the heating unit. 25
- 30

In testimony whereof, I have hereunto subscribed my name this sixteenth day of January, 1924.

ERNEST E. SUTHERLAND.
